UNITED STATES PATENT OFFICE.

JOHN E. STOREY, OF LEICESTER, ENGLAND.

MEANS FOR SUPPORTING ARTICLES OF REGULAR OR IRREGULAR FORM.

1,153,727.

Specification of Letters Patent. Patented Sept. 14, 1915.

Application filed November 24, 1914. Serial No. 873,846.

To all whom it may concern:

Be it known that I, JOHN EDWARD STOREY, a subject of the King of Great Britain, residing at Leicester, in the county of Leicestershire, England, have invented certain new and useful Improvements in Means for Supporting Articles of Regular or Irregular Form, of which the following is a specification.

My invention relates to means for holding, 10 securing or supporting single articles of regular or irregular form, for obtaining a more or less equal distribution of pressure or load over them. The apparatus may also be used for holding, securing or supporting, 15 with one application of pressure, several articles of equal or unequal sizes, or having various forms.

The object of the present invention is to construct such apparatus in a cheap and efficient manner. Apparatus constructed according to this invention does not require the good work and necessary expense involved in mounting beams in pairs on other beams by means of pivots, which other beams are 25 again mounted in pairs, and so on until the desired flexibility and number of points of contact are obtained; or in making bodies with cylindrical or spherical sliding surfaces mounted in a similar manner to the 30 beams previously referred to, which have hitherto been used in such form of apparatus.

The present invention consists in the combination with a suitable base or support, of 35 two series of movable bodies arranged normally in two lines, one series being in contact with the base or support and the other series being in contact with the first series, or suitably supported thereby, and arranged 40 farther from the base or support. Those movable bodies in contact with the base or support, are each capable of automatically and separately moving longitudinally with respect to the base or support. Those movable bodies which are arranged farther from 45 the base or support, are each capable of automatically and separately moving longitudinally with respect to the base or support and also automatically and separately in a 50 direction at right angles to the base or support.

According to the present invention I preferably employ a series of links, forming what may be called a chain, in which each 55 alternate rivet (except the end rivets) is so connected to a straight or curved base or

support, that it may freely slide longitudinally thereon. The end rivets are pivoted to the base or support. As adjacent sliding rivets move with relation to each other, the 60 pair of links between such rivets will form different angles, and the apices will consequently vary in distance from the base, and some of them will move longitudinally with respect to the base. Movement of one pair 65 of links produces movement in one or more adjacent pairs of links.

It will be understood that one set of alternate rivets on the adjacent parts of the links form one series of movable bodies, and the 70 other set of alternate rivets, or the adjacent parts of the links, form the other series of movable bodies. When the apices of a chain so formed are brought into contact with an irregular shaped body, one apex will first 75 come into contact with the body and will be pressed toward the base or support. The apex of one pair of links being depressed, causes other apices to rise until some or all of them, in turn, come into contact with 80 other points of the body to be gripped or supported. The links are preferably formed with straight parallel sides, but, if desired, they may be of other shape.

In some cases the one set of rivets are not 85 arranged concentric with the projecting ends of the links, but at a short distance from such ends, thus increasing the degree of flexibility and enabling each pair of links to have two gripping or supporting points. 90

In some cases the projecting apices of the links may be fitted with pads which are pivoted thereto, thus enabling the apparatus to accommodate itself more readily to various shaped articles. In lieu of the pads the 95 apices of the links may be provided with rollers, and in some cases the rollers may be fitted, not only to the apices of the links, but to the bases of the links, and they may be of such a diameter that an apex roller is in 100 contact with two of the base rollers, thus taking the strain off the links.

The base or support carrying the chain may be moved toward the article or articles to be gripped or supported, in any convenient or usual manner. It may be pivoted at or toward one of its ends, to a fixed point.

Various methods of carrying the invention into effect are shown in the accompanying drawings, in which:

Figure 1 is a side elevation of part of a vise and Fig. 2 is a section on the line 2-2

of Fig. 1. Fig. 3 is a side elevation of a modified construction. Fig. 4 is a side elevation of part of a machine, showing separate articles of different sizes or shapes being held. Fig. 5 is a side elevation of the gripping or holding device as applied to a bacon-slicing machine. Fig. 6 is a side elevation of part of a machine for drawing, rolling or straightening metal bars, sheets or tubes. Fig. 7 shows a further modification of the invention applied to a vise, and Fig. 8 is a section on the line 8—8 of Fig. 7. Fig. 9 shows separately one of the links used in the construction shown in Figs. 7 and 8. Fig. 10 shows how the apparatus of the form shown in Fig. 3 may adjust itself to an irregular shaped article. Fig. 11 is a vertical section showing another modification.

Referring to Figs. 1 and 2, the base or support consists of two outer plates a , a , secured to a block a' , by screws a^2 . The plates a have internal grooves a^3 . The chain consists of links b , connected together by pivots b' , b^2 , b^3 . The pivots b' connect the end links of the chain together, and they are riveted or otherwise fixed to the block a' , thus fixing the ends of the chain to the base or support. The pivots b^2 may be simple rivets, as shown in Fig. 2, connecting the links b with freedom of motion at their apices; or they may be screws, two of which are shown at the left side of Fig. 1, screwing into the side links of the chain. When the pivots b^2 are screws, they may be tightened to retain the links b in the position they have assumed after gripping an article or articles. The pivots b^3 are longer than the width of the chain, and their ends are located in the grooves a^3 and freely slide therein to enable the apices of the links to adjust themselves to an irregular surface. It will be noticed that the pivots b' are arranged concentrically with respect to the outer ends of the links, as shown in Fig. 1, so that two links form a single apex.

The construction shown in Fig. 3 is similar to that shown in Figs. 1 and 2, except that the pivots b^2 are arranged at a greater distance from the outer ends of the links than shown in Fig. 1, thus producing two points to contact with the object, as shown in Figs. 3 and 10.

In the construction shown in Fig. 4 the links, b , are provided with pads or blocks, c , which can freely rock on the pivots b^2 , thus enabling each pair of links to be instrumental in gripping two articles, e , e , of equal or unequal dimensions, or two separate stacks of articles as shown. Pressure is applied to the base a by means of the screw x .

Fig. 5 shows a construction somewhat similar to that shown in Fig. 4, suitable for application to a bacon-slicing machine. The base or support, A , is curved and is pivoted

at one end to a fixed bar, d , and is provided, at the other end, with a pawl, A' , engaging with the rack, d' .

Fig. 6 shows two sets of gripping devices arranged to grip an object, e' , between them. In this form of the apparatus the pivots b^2 are provided with rollers, f , thus enabling it to be used for drawing, rolling or straightening metal bars or tubes. The pivots, b^3 , are also provided with rollers f' . The rollers f' may roll on a surface a^4 , to facilitate the longitudinal movement of the pivots b^3 in the grooves a^3 .

The gripping device shown in Figs. 7 and 8 is a modification of that shown in Fig. 6. In this construction the rollers f , f' are of such diameters that they are actually in contact with each other, thus relieving the links b of all strain. The links b are not actually pivoted together but are flexibly connected together at their adjacent ends by means of the rollers. As shown in Fig. 9, each link b has at one end a portion, b^{20} at right angle to the main part b , which is equivalent to the pivots b^2 in Figs. 1 to 6, and each link b , has, at its other end, two parts b^3 and b^{30} , which are equivalent to the pivots b^3 in Figs. 1 to 6. The parts b^3 are located within the groove a^3 , and the parts b^{30} enter the ends of the rollers f' . The parts b^{20} enter the ends of the rollers f . The rollers f' roll upon the surface a^4 , and an incline, a^{14} , is provided at each end of the base or support a to support the end rollers f . According to the positions of the rollers f , the links b assume various angles, and the parts b^3 slide along the groove a^3 as in the constructions shown in Figs. 1 to 6. Fig. 7 shows an article, e^2 , having one straight and one curved side, gripped between two of the tools or devices.

In the construction shown in Fig. 11, the base consists of a block a' and side plates a , connected by screws a^2 as in the previous constructions. The block a' has a flat surface a^4 upon which the pieces F' slide longitudinally with respect to the base. Between the pieces F' are located other pieces F , which are capable of sliding upon the inclined surfaces of the blocks F' , and therefore moving longitudinally with respect to the base and at right angles thereto. The pieces F are formed with holes F^2 through which pass retaining wires F^3 riveted in the side plates a . These wires F^3 allow considerable movement to the pieces F , but not sufficient to allow the pieces F' to escape. The sliding surfaces in this construction are flat and can therefore be readily made at small cost. The block a' has an incline a^{14} at each end to support the end pieces F and to enable them to slide in the desired directions.

What I claim is:

1. In apparatus for holding articles of

unequal size or irregular form, the combination of a base, a series of movable bodies in contact with said base, means for retaining said movable bodies with respect to the base while allowing each of them to automatically and separately slide longitudinally thereon, a second set of movable bodies supported by the first set of movable bodies and arranged at a short distance from the base, means for connecting this second set of movable bodies to the base while allowing them to have automatic and separate motion longitudinally with respect to the base and also at right angles thereto, substantially as set forth.

2. In apparatus for holding articles of unequal size or irregular form, the combination of a base, a series of movable bodies consisting of alternate rivets of a chain and the adjacent parts of the links in contact with said base, means for retaining said movable bodies with respect to the base while allowing them to move longitudinally thereon, a second set of movable bodies consisting of the other alternate rivets of the chain and the adjacent parts of the links arranged at a short distance from the base, means for connecting this second set of movable bodies to the base while allowing them to have motion longitudinally with respect

to the base and also at right angles thereto, substantially as set forth.

3. In apparatus for holding articles of unequal size or irregular form, the combination of a base having longitudinal grooves therein, a chain arranged in zigzag form, the end rivets of the chain being fixed to the base, other alternate rivets projecting beyond the sides of the chain and the ends of these last mentioned rivets being located in the said longitudinal grooves with capability of sliding therein, substantially as set forth.

4. In apparatus for holding articles of unequal size or irregular form, the combination of a base consisting of a block and side plates each plate having a longitudinal groove therein, a chain having its links arranged in zigzag form, the end rivets of the chain passing through the base, alternate pivots of the chain projecting beyond the sides thereof, and the ends of these pivots being located within the grooves in the side plates, substantially as set forth.

In witness whereof I have hereunto set my hand in presence of two witnesses.

JOHN E. STOREY.
